UNITED STATES PATENT OFFICE.

JAMES McDONALD BURNETT, OF WESTON-BY-WELLAND, AND JOHN ALFRED FULL-
LOVE, OF MARKET HARBOUROUGH, ENGLAND.

ACCUMULATOR PLATE.

Application filed May 6, 1924. Serial No. 711,465.

This invention relates to accumulator plates.

One object of the invention is the provision of an accumulator plate having an insulating frame secured around the edge thereof whereby a plurality of such accumulator plates arranged side by side will be positively prevented from making electrical contact with one another.

10 Another object is the provision of means for positively and rigidly securing, on an economic and commercial scale, an insulating frame around the edge of an accumulator plate.

15 Another object is the provision of an accumulator plate built up of a number of cast lead units and having an insulating frame secured around the edge thereof said units and frame being held together in a 20 single structure of greater rigidity than an ordinary lead accumulator plate.

Other objects and advantages will appear hereinafter.

25 Two embodiments of the invention are illustrated in the accompanying drawings and the same will now be described it being understood that the particular constructions and arrangements illustrated are susceptible of various modifications without departing 30 from the scope of the appended claims.

In these drawings:—

Figure 1 is a perspective view of one of the wooden frame members of one of the embodiments.

35 Figure 2 shows in perspective in elevation and in section views of the frame members arranged in a position illustrating one stage in the process of manufacture of the plate.

40 Figure 3 shows in side elevation and in section the finished plate enclosed in its frame.

Figure 4 is a plan view of two disassembled adjacent frame members of the other embodiment.

45 Figure 5 is a sectional end elevation of the same.

Figure 6 is a sectional side elevation of all four frame members shown in their assembled relation with respect to one another, and

50 Figure 7 is a side elevation of a finished plate enclosed in a frame formed of frame members such as those illustrated in Figures 4 to 5.

Referring first to Figures 1-3 the plate comprises a number of units (such as that described with reference to Figure 1 of the drawings of Letters Patent of the United States, No. 1,564,524 granted to me Dec. 8, 1925) and four wooden frame members 2. The units, as described in the specification aforesaid are of square formation and have a number of perforations 3 adapted to accommodate accumulator paste and symmetrical grooves 4 formed along their edges; and the frame members have each a groove 5 in one longitudinal edge and inwardly tapering holes 6 leading to said groove from the opposite longitudinal edge.

As shown, the units are arranged edge to edge to form a square or rectangular mosaic and the frame members are arranged around the outside edge of such mosaic with their grooves inwards. The whole is bound together in this correlation by means of some acid proof conducting material, such as antimonial lead (which is of greater rigidity than lead), cast in the hidden communicating channels which run between all the adjacent pairs of units and also between the frame members and the outside units.

55 In the construction of the arrangement the plate proper may be first formed in the manner described in the specification accompanying the copending application aforesaid except that no metallic frame or lug is formed, the frame members being afterwards secured therearound by clamping them in position and pouring antimonial lead through the tapering holes 6 so as to fill the concealed channel between the plate proper and the said frame members; or the separate units and frame members may be bound together by one casting operation of the antimonial lead. In this latter case the frame members are arranged in a template 60 in the relation shown in Figure 2 and the units are arranged and clamped by suitable clamps in the position within the frame members shown in Figure 3. Antimonial lead is then poured or forced through the tapering holes 6 and percolates through the network of communicating intersecting channels running between all the adjacent pairs of units and also between the outside units and the frame members and thereby positively secures the whole structure together.

65 By virtue of the tapering holes 6 being 110

filled with antimonial lead, positive joints are constituted, as will be readily understood, between the frame members and the accumulator plate proper.

- 5 Referring now to Figures 4 to 7 these figures illustrate the construction of an embodiment of the invention in which, in the first place, the antimonial lead is not exposed outside the frame members except 10 where desired for electrical connection, in the second place, the tapering holes 6 are dispensed with, and in the third place a supporting lug of the antimonial lead is cast into the structure during the operation 15 of securing the several parts together.

As shown in Figures 4 to 5 each frame consists of four members two of which, 2^a are provided with grooves 5^a extending the whole length thereof and the other two of 20 which, 2^b are provided with grooves 5^b which do not extend the whole length thereof but terminate at points adjacent the two ends as shown.

25 Thus by assembling the four frame members in the manner shown in Figure 6 a continuous channel is formed running round the inside edge of the frame which channel does not communicate with the outside edge of the frame.

30 A further feature of this embodiment resides in the fact that the grooves 5^a and 5^b are undercut as shown in Figure 5, so that the securing of the frame members to the antimonial lead within the grooves thereof 35 and therefore to the plate proper is rendered positive without employment of the tapering holes 6. The straight sided holes 7 at the two ends of the grooves 5^b are formed, prior to such undercutting of said 40 grooves 5^b, in order to render it possible to insert an undercutting tool into the groove.

The plate proper and frame members such as above described (arranged in the 45 relation shown in Figure 6) are built and incorporated into one structure precisely as in the case of the embodiment illustrated in Figures 1 to 3 except that instead of antimonial lead being poured into the network of communicating channels through 50 the tapering holes 6, it is all poured through one large elongated hole or slot 8 formed in one of the members 2^a as indicated in Figure 7. This hole or slot moreover permits of the casting on of a supporting and 55 terminal lug 9 of antimonial lead integral with the antimonial lead which cements the units and frame together.

Instead of being built up of units having 60 symmetrical grooves around their edges, plates of varying thickness and having wooden frames as in the embodiments above described may be built up of units the edges of which are recessed to one side (as shown 65 in Figure 3 of the drawings of the Letters Patent aforesaid) so that symmetrical

grooves may be formed by placing a pair of units face to face. In this case pairs of units, placed in this manner face to face, are treated as single units to build up the plate proper in the manner described in the specification of the Letter Patent aforesaid with reference to Figure 6 of the drawings accompanying the same. In this case frame members of proportional thickness are of course used to enclose the plate. 70

Where a block battery is required this may be done by first drilling similarly disposed holes 8 (Figure 2) through similar frames of each of a number of plates, next placing the plates one against the other in block formation with these holes in registration and finally cementing the plates into one block by filling these registering holes with antimonial lead. These holes may be made of smaller diameter in the middle than at the ends in order to make the securing together of the plates more positive. 80

90 In any of the aforescribed embodiments, the holes 3 may obviously be made bevelled as described with reference to Figure 2 of the drawings accompanying the specification of the Letters Patent aforesaid.

What we claim and desire to secure by Letters Patent is:—

1. An accumulator plate structure comprising an accumulator plate proper, an insulating frame secured around the edge thereof and a connecting element cast between said insulating frame and said plate proper for securing the same together, said connecting element extending into a recess in said insulating frame which is of such shape that said frame is positively locked to said connecting element irrespective of the force of adhesion. 100

2. An accumulator plate structure comprising an accumulator plate proper, an insulating frame secured around the edge thereof and a connecting element cast between said insulating frame and said plate proper for securing the same together, said connecting element extending into recesses in said insulating frame and said plate proper which recesses are of such shape that said insulating frame and said plate proper are both positively locked to said connecting element irrespective of the force of adhesion. 110

3. An accumulator plate structure comprising an accumulator plate proper and an insulating frame secured around the edge thereof, said insulating frame and said plate proper being secured together by the process of casting therebetween an integral connecting element. 115

4. An accumulator plate structure comprising an accumulator plate proper, an insulating frame secured around the edge thereof and a conducting connecting element cast between said insulating frame 120

and said plate proper for securing the same together, said connecting element extending at one point completely through the frame to the outside edge thereof so as to thereby constitute a terminal of the plate proper.

5. An accumulator plate structure comprising a number of units together constituting the accumulator plate proper, said units having formed therein recesses which co-operate to form channels running between said units, an insulating frame around the outside edge of the combined units, said insulating frame having formed therein an

undercut groove around the inside edge 15 thereof which groove co-operates with recesses of the outside units to form a channel running between said frame and the outside edge of the combined units, and a connecting framework of more rigid material 20 than the material of the units cast both into said former channels and said latter channel and securing said units and said frame together into a rigid structure.

In witness whereof we affix our signatures.

JAMES McDONALD BURNETT.
JOHN ALFRED FULLILOVE.
